United States Patent

Des. 240,380
Patented July 6, 1976

240,380

WALL MOUNTED SUPPORT FOR TELEVISIONS OR THE LIKE

Henry E. Jepsen, Whittier, Calif., assignor to
Corvex Corporation, Santa Fe Springs, Calif.

Filed Jan. 13, 1975, Ser. No. 540,326

Term of patent 14 years

Int. Cl. D6—04

U.S. Cl. D6—114

FIG. 1 is a perspective view of a wall mounted support for televisions or the like showing my new design;

FIG. 2 is a side elevational view taken from the right of FIG. 1;

FIG. 3 is a bottom plan view of FIG. 1;

FIG. 4 is a perspective view of a second embodiment of the design of FIG. 1;

FIG. 5 is a side elevational view taken from the right of FIG. 4;

FIG. 6 is a bottom plan view of FIG. 4.

I claim:

The ornamental design for a wall mounted support for televisions or the like, as shown and described.
